UNITED STATES PATENT OFFICE.

JAMES W. WARD, OF PITTSBURGH, PENNSYLVANIA.

REPAIR AND PRESERVATION OF BOOKS.

Application filed March 6, 1925. Serial No. 13,493.

This invention relates to the repair and preservation of books and seeks particularly to repair record books in such a manner that the leaves will be reenforced and renewed 5 and may be handled freely without further deterioration through a long period of time. In books which are consulted constantly, such, for instance, as public records, the leaves break near the back as a result of the 10 frequent folding and, prior to my invention, there has been no satisfactory means for repairing the books in which such signs of wear have appeared. By the practice of my invention, the damaged books are repaired 15 in a practical and permanent manner adding strength and flexibility to the leaves.

In the accompanying drawings:

Figure 1 is an end view of a book prepared for the application of guards or fillers; 20 Figure 2 is a similar view showing a slight variation in the arrangement of the leaves to be rebound;

Figure 3 is a perspective view of leaves to which guards or fillers have been applied; 25

Figure 4 is an end view of the repaired book.

In repairing an old book in accordance with the present invention, the cover is, of course, removed. I then cut off the fold of 30 each signature sufficiently to remove all paper touched by the old glue and produce evenness in the frail worn portion caused by the glue. With the book lying upon one side, as indicated in Fig. 1, a definite 35 number of leaves, say ten, as indicated at 1, are then lifted from the top of the book without further change, and placed upon a convenient rest upper face downward. A second block of ten leaves, 2, 40 is then removed and a strip about one-eighth of an inch wide is cut from the trimmed back edge thereof. This block of leaves is then placed upon the first block so that the leaves will be in consecutive order, and a third 45 block of leaves is then removed and placed upon the second block. A fourth block is then removed and trimmed just as the second block was trimmed, the process being repeated until all the leaves have been 50 arranged in blocks of equal thickness as shown in Figure 1.

If the book should be rather thick, the leaves are arranged in groups of blocks, as shown in Figure 2, trimmed to three different widths, the block 3 retaining its original width minus the slight reduction made in

removing the glue, the block 4 being reduced approximately one-eighth of an inch, and the block 5 being reduced approximately 60 one-fourth of an inch.

To the trimmed back edge of each sheet, there is now pasted a guard or filler consisting of a strip of high grade new linen paper 6 half the thickness of the leaf and which, for most books, will be about three 65 inches wide. The filler strip is secured to the leaf in such manner that the overlap will be the same as the difference in width of adjacent blocks or leaves. The leaves and attached filler strips are then brought into 70 such position that the overlaps will all be in the same vertical plane in superposed relation and they are placed in the drying press with waxed paper or the like between 75 the leaves. Left in the press for a time sufficient to permit thorough drying of the paste, when the leaves are removed it will be found that the thickness of the overlap has been reduced and the respective leaves and strips have been firmly united in a 80 smooth joint. The filler strips are then folded or doubled on themselves toward the respective leaves, as indicated at 7 in Figure 3, to bring the free edges of the strips within 85 about one-eighth of an inch of the trimmed edge of the leaf, after which the blocks of leaves are again arranged with their back 90 trimmed edges in the staggered relation shown in Figure 1 or Figure 2, as the case may be, thereby bringing the alternate groups of overlaps over the spaces between 95 the leaves and the free edges of the folded filler strips. The extra thickness caused by the overlap is thus accommodated and the folded filler strip will have the same thickness as the leaf to which it is attached. The leaves are thus repaired without adding to the thickness of the book and this is true whether one page or more is taken at each 100 separate width. The fillers are then trimmed by cutting away their folded edges so that they will be even after which they are bound by sewing or otherwise connecting the superposed fillers at their rear edges, as shown in 105 Figure 4, or they may be secured in a loose leaf binder. Of course, if a loose leaf binder is to be used it will be necessary to form openings through the fillers to receive the binder posts or rings, and it may be necessary to paste or glue together the plies of each filler, at least for a portion of their 110 widths.

This invention adds new papers in the binding edge of the book, thereby strengthening the volume, and also provides a more flexible carrier for the leaf so that the sheet 5 will fold or bend in the new strip and thus relieve the old frail brittle paper.

Having fully described my invention what I claim as new and desire to secure by Letters-Patent, is:—

- 10 1. A method of repairing books which includes attaching to each leaf of the book one edge portion of a filling strip having a thickness one-half that of the leaf, arranging the unions of the leaves and strips in staggered relation, folding the strips toward the respective leaves and spacing the free edges of the strips from the edges of the leaves, and binding the strips.
- 15 2. A method of repairing books which includes attaching to each leaf of the book a filler strip having a thickness one-half that of the leaf, arranging the unions of the leaves and strips in staggered relation, folding the strips toward the leaves and spacing 20 the free edges of the strips a distance from the leaves substantially equal to the width of the union between a leaf and a strip, and binding the strips.
- 25 3. A method of repairing books which includes trimming the binding edges of the book leaves to remove all adhering binding material, then additionally trimming some of the leaves whereby to produce groups of leaves with all the leaves in each group uniform in width, securing a filler strip to the

binding edge of each leaf with the overlap of the strip equal in width to the difference between the widths of the leaves, arranging the overlaps in staggered relation, folding the strips toward the leaves with the free 40 edge of the strip spaced from the leaf a distance equal to the width of the overlap, and binding the strips.

4. A book leaf having a filler strip attached to its rear edge, the strip including 45 a portion which is attached to the leaf and another portion which lies in the plane of the leaf against the first-mentioned portion and terminates in spaced relation to the leaf.

5. A book leaf having a folded filler strip 50 attached to its rear edge and overlapping said edge, the thickness of the strip being one-half the thickness of the leaf and one edge of the strip being free and spaced from the rear edge of the leaf a distance equal to 55 the width of the overlap of the strip upon the leaf.

6. A book having leaves of different widths arranged in groups with the leaves in a group of uniform width, folded filler 60 strips each attached along one edge to the rear edge of a leaf with an overlap equal in width to the difference in width of the leaves and the free edge of the strip spaced from the leaf a distance equal to the width 65 of the overlap, and means binding the strips.

In testimony whereof, I have signed this specification.

JAMES W. WARD.
